UNITED STATES PATENT OFFICE

ORRIN C. BURDICT, OF BUFFALO, NEW YORK.

BOLT-FORGING MACHINE.

SPECIFICATION forming part of Letters Patent No. 285,876, dated October 2, 1883.

Application filed March 27, 1883. (No model.)

To all whom it may concern:

Be it known that I, ORRIN CLARK BURDICT, of Buffalo, in the county of Erie and State of New York, have made an invention 5 of certain new and useful Improvements in Bolt-Forging Machines; and I do hereby declare that the following, in connection with the accompanying drawings, is a full, clear, and exact description and specification of the 10 same.

This invention relates to the forging of the heads and angular shoulders of round-stemmed bolts, commonly called "carriage-bolts." Previous to this invention, so far as I know, 15 such bolts have been generally forged in the following modes: According to one mode bolt-blanks have been forged from square rods by reducing a portion of each blank to the round form for the stem. This mode produces a 20 bolt with the sides of the square shoulder of the full size of the diameter of the round stem, but it is exceeding costly. Another mode is to use round rods of the size of the stem, and to form the shoulder by driving endwise or 25 "upsetting" the end of the rod while it is clamped in dies which are partly angular and partly round, with the round portions materially smaller in diameter than the round rod employed. This mode, although comparatively 30 inexpensive, produces a bolt-blank with an angular shoulder of scant or insufficient dimensions and with the rounded stem reduced in diameter beneath the shoulder; hence the bolts are objectionable for many purposes. 35 Another mode of forging carriage-bolts from round bolt-blanks is to produce the angular shoulder from round bolt-blanks by a succession of operations upon it, the metal to form the shoulder being thickened at one operation, 40 and being forged to its square form by a succeeding operation. This mode produces round-stemmed bolt-blanks having angular shoulders whose sides are the full size of the diameter of the round stem; but the mode is comparatively 45 costly, because of the necessity of handling and operating upon the bolt-blank at least twice for the formation of the head and shoulder. Another objection to the ordinary modes of forging the heads and square 50 shoulders of round-stemmed bolt-blanks is that they do not result in the production of blanks of practically uniform length, because the

blanks slip unequally between the dies while the heads and shoulders are being formed by the endwise driving of the metal, technically 55 termed "upsetting."

The principal objects of the present invention are to forge the head and shoulder of a carriage-bolt at a single operation, and with the sides of the square shoulder of the full size 60 of the diameter of the round stem, and also to make the bolts, when forged, of practically uniform length from the under side of the head to the point of the stem, notwithstanding 65 small irregularities in the lengths and diameters of the round blanks used for the purpose, and irregularities in the presentation of the blanks to the machine.

To these ends the invention consists of certain combinations of mechanical devices which are recited in detail at the close of this specification. In order that these combinations may be fully understood, I have represented in the accompanying drawings, and will proceed to describe, a machine embodying them 75 in the best form which I have thus far devised for the purpose, it being understood that the mechanism of the machine may be modified as circumstances or the views of divers constructors and users may render expedient. 80

Figure 1 of the said drawings represents a plan of the said machine with some parts removed. Fig. 2 represents a vertical transverse section of the same, at the line *xx* of Fig. 1, viewed from the back end. Fig. 3 represents a corresponding section, at the line *yy* of Fig. 1, viewed from the front end. Figs. 4 to 8, inclusive, represent views of detached parts of the said machine, designated by the same letters of reference as the same parts in 90 the other figures.

The various moving parts of the machine are secured to or connected with a strong bed-frame, A. The devices which operate directly upon the bolt-blank for forging its angular shoulder and head are the dies B B', the heading-tool C, and the stop D. The dies B B' are blocks of metal (steel by preference) whose adjacent faces contain cavities *aa*, Figs. 7 and 8, each of which is partly angular and partly semi-cylindrical, and is the counterpart of half of the part of the forged bolt which is to be produced in the dies, the dies being thus divided dies whose adjacent faces can be separated to receive

the bolt-blank and to discharge it, but are held together during the forging, so as to form a matrix for the bolt. One of these dies, B, is by preference made stationary by being secured 5 to the frame by means of a clamp, b. The other die, B', is movable toward and from the stationary or fixed die B, and for this purpose the said movable die is, by preference, secured by means of a clamp, b', to a swinging die-holder, E, which is pivoted at its lower end or shank to the frame A of the machine. In order that this movable die B' may be moved toward the fixed die B, and may be held in its proper positions, a slide, F, is provided, which 10 is fitted to slide in a guide-box, G, with its rear end, d, within the range of motion of the die-cam H, which is secured to and revolves with the driving-shaft J of the machine. The said die-slide is fitted with a toggle-joint, I, 15 whose ends are received in sockets formed in the adjacent sides of the swinging die-holder E and slide F. When the said slide F is in its rearmost position, the said toggle-joint I is at a considerable angle with the plane in 20 which the swinging die-holder E swings, and when the said slide is forced forward by the action of the cam H the said toggle is moved more nearly into the plane in which the swinging die-holder E swings, and this die-holder 25 and the movable die B' are therefore forced toward the fixed die B. When the form of the cam H permits the slide F to retrograde, this slide is retrograded by a spring, e, Fig. 4, which is contained in a cavity within the 30 slide, and as the retrogression of the slide permits the toggle to relieve the swinging die-holder E, that die-holder and the movable die B' are moved away from the fixed die B by a spring, f, thereby leaving the faces of the 35 dies separated or open for the entrance of a bolt-blank.

The heading-tool C is arranged endwise opposite the cavity of the dies B B' when they are closed. Its head has a cavity in it which 40 is the counterpart of the bolt-head to be forged, the form of bolt-head being by preference that shown in Fig. 9, and known as a "beveled head." The shank of this heading-tool is secured in the header-slide K, which is constructed to move in guides secured to the frame 45 of the machine, and in directions endwise toward and from the cavity of the dies B B', so that the heading-tool has a reciprocating motion. In order that the heading-tool and its 50 slide may be thus moved, the latter is connected by a connecting-rod or pitman, L, with the cranked portion of the driving-shaft J.

The position of the bolt-blank when in the dies and during the forging operation is determined by the stop D, which is held axially of the cavity of the dies in a socket formed in the frame of the machine, its shank m being by preference abutted against an adjusting-screw, g, so that the point of the stop may be 60 readily adjusted to its proper position relatively to the dies B B'. In order that this stop may be used to eject the forged bolt, it is

made movable endwise in its socket, and is connected by a lever, L', with a spring, N, Fig. 5, which, acting through the intervention of a connecting-rod, M, tends to force the stop toward or into the cavity of the dies and to start or eject the bolt therefrom. In order that the stop, when moved by the said spring N, may be retracted sufficiently when the bolt-blank is inserted between the dies, the connecting-rod M is connected with an elbow-lever, O, which is pivoted to the frame of the machine, with the end of its shorter arm p within the range of motion of the projecting rim 80 of a cam, P, which is secured to the driving-shaft J, so that the stop may be retracted in its socket when the bolt-blank is being entered in the die-cavities. The spring and cam above described constitute the devices for moving 85 the stop, so that it may operate as an ejector for the forged bolt.

In the said machine the bolt-blank to be forged is entered between the dies, from above them, while they are open, by reason of the 90 movable die B' being drawn sidewise away from the fixed die B, and while the heading-tool C is drawn backward in the machine. In order that the bolt-blanks may in succession be properly and automatically applied to the dies when they are open, the feeder R is provided. This feeder is arranged to move between the dies at one side and the heading-tool at its opposite side, and it has by preference the form and construction represented in 95 the drawings, being a swinging nippers having two jaws, n and n'. One of these feeder-jaws, n, has a shank, n², which is fitted to swing up and down upon a pivot secured to the frame A. The other feeder-jaw, n', has a 100 lever-shank, n³, which is connected by a pivot with the first feeder jaw, n, and this lever-shank is extended above the pivot and is fitted with a pin, n⁴, by operating on which the said jaw n' may be moved from the first jaw, n, so 105 that the feeder-jaws are open to receive a bolt-blank between them. The feeder is moved upward and downward in the machine by means of a rock-shaft, S, which is fitted to rock in bearings j j, secured to the frame of the 110 machine. This rock-shaft has an arm, k, which is slotted as its end to receive a pivot extending from the swinging feeder-shank n², so that when the said shaft is rocked in one direction the feeder R is raised until the notches of its 115 jaws n n' are above the dies B B', and when the rock-shaft is rocked in the reverse direction the feeder is lowered until the notches of its jaws are opposite the cavity of the dies in front of the feeder and the end of the heading-tool in its rear. The rock-shaft S receives its 120 rocking movement by preference from the slide K of the heading-tool. For this purpose the feeder rock-shaft is constructed with a barrel, w, which is slotted longitudinally with a helical groove, w', Fig. 6, in which a pin, r, secured to the slide K of the heading-tool, is constructed to slide. The groove is of such form that when the heading-tool retrogrades in the machine the 125 130

feeder is depressed to its lowest position, and it pauses or remains there until the dies are closed sufficiently to hold the bolt-blank, and while the heading-tool is moved toward the dies the feeder is raised to its highest position, and it pauses or remains there until the bolt-blank is inserted into the notches of its jaws by an attendant. The two pauses above mentioned in the operation of the feeder are obtained in part by constructing the end portions of the spiral groove w' straight or parallel with the movement of the pin r , which engages in it, and in part by the slow movement of the heading-tool when its crank is passing centers.

In order that the feeder-jaws, when raised, may be opened to receive the bolt-blank and may close upon the blank as they commence to descend, a fixed cam, T , is secured to the frame of the machine, with its cam protuberance t within the range of movement of the pin n' , projecting from the lever-shank of the movable feeder-jaw n' , so that when the feeder is raised the cam protuberance operates upon the said pin n' and compels the movable jaw n' to separate from the fixed jaw n sufficiently to admit the bolt-blank. A spring, r' , also is provided to move the movable feeder-jaw in the reverse direction when by the lowering of the feeder the pin n' leaves the cam protuberance t , thus causing the feeder-jaw to close upon and hold the blank with a yielding pressure. When the blank has been seized by the dies this same spring permits the movable feeder-jaw n' to separate from the fixed jaw n as the feeder is moved upward, and to leave the bolt-blank in the grasp of the dies.

In order that the attendant may readily enter the bolt-blank endwise into the notches of the feeder-jaws, the clamp b' , which holds one of the dies, is formed with a notched end, so that the adjacent ends of the die-clamps b b' form a feed-guide, by which the bolt-blank may be readily guided into the notches of the feeder R when it is raised.

When the machine is to be operated, the stop D is so adjusted that when it is retracted in its socket to the farthest extent the distance between its acting end and the rear sides of the dies is equal to the length of the forged bolt-blank from its point to the under side of its head. The bolt-blanks are cut from round iron of the size of the round stem required, and so long that each contains a little more than sufficient material to form the round stem, the square shoulder, and the head. The bolt-blanks are highly heated, are picked up with tongs, and are entered, one at a time, through the guide b b' , into the feeder R , when it is raised and while the dies are closed, care being taken to so apply each blank to the feeder that the end of the blank nearest the front end of the machine is nearer the back of the machine than the position of the end of the stop D when it is in its retracted position. Then as the driving-shaft J revolves the heading-tool is drawn backward, the jaws of

the feeder close upon and grasp the blank, the dies open, the feeder descends between the dies and heading-tool and carries the blank downward between the faces of the dies to the cavities thereof, the dies close upon the blank, the heading-tool is driven endwise toward the rear end of the blank, the feeder R is raised and its jaws slip from the blank as the heading-tool approaches it, so that the feeder is out of the way of said tool, and the heading-tool advances against the end of the bolt-blank protruding from the die-cavities. As the stop D prevents the bolt-blank from slipping more than a certain distance endwise between the dies and then forms a firm abutment for the bolt-blank, the whole of the portion of the blank rearward of the round parts of the die-cavities cannot escape the action of the heading-tool C , which, in its continued advance, upsets and thickens the heated metal sufficiently to form a full square shoulder and a full bolt-head, the surplus material, if any, escaping between the rim of the heading-tool and the rear sides of the dies in the form of a fin, which can be dressed off after the bolt-blank is cold. As each bolt-blank during the forging of its head and shoulder has its point sustained by the stop D at the same distance from the rear faces of the dies B B' , against which the under side of the head of the bolt is formed, the lengths of all the bolt-stems from their heads to their points must of necessity be practically the same.

After the operation of forging is completed the heading-tool C is withdrawn, the dies relax their grasp upon the bolt, and the stop D is forced forward by the spring N , so as to loosen the bolt from the dies, (in case it adheres to one of them,) and as the dies open the forged bolt drops through a cavity in the frame of the machine. Meanwhile the succeeding bolt-blank has been introduced into the raised feeder R by the attendant, so that it is operated upon in turn.

I find it expedient to make the round portions of the cavities of the dies B B' no smaller in diameter than the round iron employed for blanks, so that when the dies are closed upon the blank they cannot grip it so tightly as to prevent it from slipping endwise between them (under the action of the heading-tool) until the end of the blank brings up against the stop D . I have also found it expedient to construct the closing grade s , Fig. 4, of the die-cam H of such eccentricity that the dies are not fully closed until the heading-tool has pushed the bolt-blank up to the stop D ; or, if the die-cam be constructed and set so as to close the dies fully before the heading-tool is advanced sufficiently to push the bolt-blank against the stop, the round portions of the cavities of the dies should be made slightly larger transversely than the bolt-blank, so that the latter may slip between them when first acted upon by the heading-tool, and may be pushed between the dies until its point is against the stop. I also find it expedient to construct the opening

grade of the die-cam H with a substantially concentric step, s', so that the dies at first slightly open and then pause or dwell while the stop D, acting as an ejector, is moved to 5 start the bolt endwise, thus preventing it from adhering to either die.

When the combination of dies, stop, and heading-tool above described is employed to forge angular-shouldered bolt-blanks with 10 long round stems, the dies need not extend the whole length of the stem of the bolt-blank.

The use of the automatic feeder is attended with great advantages, because the bolt-blank may be inserted in it while the preceding bolt 15 is being forged in the dies, and ample time for such insertion may be afforded by a pause of the movement of the feeder when in its raised position; hence the machine may be fed with certainty when it is running at a much greater 20 speed than would be practicable if the feeding had to be done by hand directly into the cavities of the dies, and the dies had to remain open long enough for that purpose, the practical difference being the production of a 25 largely-increased number of forged bolts, as compared with the production by machines in which the blanks are fed by hand directly to the dies.

In order that the machine may be driven by 30 a belt, a belt-pulley is secured to one projecting end of the driving-shaft, and a fly-wheel is secured to the opposite projecting end of said shaft.

The arrangement of the feeder so that it operates between the dies and the heading-tool 35 is important, because when it is constructed to operate in this relationship to the other devices it can take hold of the bolt-blank by the part corresponding with the neck or shoulder 40 of the forged bolt. This relationship therefore enables the machine to be employed for the manufacture of bolts so short that their stems are wholly received within the cavities of the dies.

45 An essential feature of my invention is the combination, with the other devices, of divided

dies which can be separated to receive the bolt-blank between them by a lateral movement of it, and to relax their grasp upon the bolt-blank for its discharge. Machines for 50 making rivets and screw-blanks, containing devices corresponding with some of those employed by me, have heretofore been constructed with solid dies of circular section; but such dies cannot be successfully used for the forging of angular-shouldered bolt-blanks, and are objectionable, because, if the iron should be strongly upset in such a die, great force would be required to eject the headed bolt-blank, the grasp upon which would not be relaxed. 55 Moreover, as solid dies do not open to receive and to discharge the article on which they operate by a lateral movement of it, the entrance and discharge of the article require it to be moved longitudinally a distance equal to the 60 length of its stem, and the devices of the machine containing such solid dies have to be moved correspondingly; hence such solid dies are not the equivalents of the divided bolt-dies 65 described by me, and I do not claim such solid 70 dies, either separately or in combination with other devices.

I claim as my invention—

1. The combination, substantially as before set forth, of the divided bolt-dies, the heading-tool, and the automatic feeder, the relationship of these devices being, as described, that the feeder operates between said dies and said heading-tool. 75

2. The combination, substantially as before set forth, of the bolt-dies, the heading-tool, the automatic feeder, and the stop which limits the distance to which the blank may be moved between the dies by the heading-tool from the position in which it is fed to said dies by the 80 feeder.

In witness whereof I have hereto set my hand this 20th day of March, A. D. 1883.
